(57) **CLAIM**

The ornamental design for an electric toothbrush handle, as shown and described.

DESCRIPTION

FIG. 1 is an isometric view of an electric toothbrush handle illustrating my new design according to an embodiment; FIG. 2 is a front elevation view of the electric toothbrush handle of FIG. 1;

FIG. 3 is a back elevation view of the electric toothbrush handle of FIG. 1;

FIG. 4 is a left side elevation view of the electric toothbrush handle of FIG. 1, the right side elevation view being a mirror image thereof;

FIG. 5 is a bottom plan view of the electric toothbrush handle of FIG. 1;

FIG. 6 is an isometric view of an electric toothbrush handle illustrating my new design according to a further embodiment;

FIG. 7 is a front elevation view of the electric toothbrush handle of FIG. 6;

FIG. 8 is a back elevation view of the electric toothbrush handle of FIG. 6;

FIG. 9 is a left side elevation view of the electric toothbrush handle of FIG. 6, the right side elevation view being a mirror image thereof; and,

FIG. 10 is a bottom plan view of the electric toothbrush handle of FIG. 6.

The features shown in dashed lines form no part of the design and are not claimed.

1 Claim, 4 Drawing Sheets
